UNITED STATES PATENT OFFICE

2,243,766

REFRIGERATION

Peter A. Nelson, Reno, Nev.

Application January 5, 1939, Serial No. 249,510

1 Claim. (CL 62—1)

This invention relates to an improved apparatus for defrosting a cooling coil and for cooling a receptacle or container by circulating a liquid by an endless route around and through said portions, respectively.

It is a primary object of this invention to provide an endless system for a fluid having means for pumping the fluid or liquid therethrough for defrosting the cooling coils of a cooling unit, for using the fluid cooled by contact with the frost on said coils for cooling an enclosed container and for employing the heat taken up by the fluid in passing through said container to defrost said cooling coils.

It is a particular object of this invention to provide apparatus to recover refrigeration losses caused by excessive frost or ice on cooling coils and other refrigerating surfaces which tend to insulate said coils from the area to be cooled, and transmitting the cooling action of said frost or ice to a zone having a higher temperature and requiring refrigeration.

It is a further aim of the invention to provide a device which may be readily associated with various forms of cooling units and with containers to be cooled without in anywise modifying the refrigerating apparatus of the cooling unit.

Still a further aim of the invention is to provide an endless conduit for defrosting the refrigerating surfaces of a cooling unit having means for by-passing the fluid by a circuitous route around a heating element to more quickly and effectively perform the defrosting operation.

Other objects and advantages of the invention will hereinafter become more fully apparent from the following description of the drawing, which illustrates a preferred embodiment thereof, and wherein:

Figure 1 is a side elevational view, partly diagrammatic, showing the preferred form of the apparatus, and

Figure 2 is a similar view showing a slightly modified form of the apparatus.

Referring more particularly to the drawing, wherein like reference characters designate like or corresponding parts in the different views, the device is adapted to be employed in conjunction with any conventional type of cooling unit such for example as a refrigerator, designated 10 and which is provided with a cooling coil or any other form of refrigerating surface 11 through which ammonia or other conventional types of refrigerants are circulated for cooling the refrigerator 10, and on which frost or ice will collect requiring defrosting. 12 designates any conven-

tional container such as a showcase not provided with a cooling unit but which requires cooling to a temperature higher than the refrigerator 10.

The parts heretofore referred to are of conventional construction and are shown merely to illustrate the application of the apparatus comprising this invention and the method by which the coils 11 may be defrosted and the showcase 12 cooled. The invention includes an endless pipe line 13 which may be formed of any suitable metal and which is adapted to be filled with a liquid having a low freezing point through the neck 14 which latter is provided with a removable cap 15.

Referring particularly to the form of the invention as illustrated in Figure 1 which constitutes the preferred form thereof, the conduit 13 is provided with a portion designated 16 which is disposed within the refrigerator 10 and which is coiled around the convolutions or legs of the cooling coil 11. If desired, the portion 16 which is in engagement with the cooling coil 11 may extend straight along the coil and be welded or otherwise permanently secured thereto instead of being spirally coiled around the portion 11, as illustrated. Conduit 13 also includes the portion 17 which is disposed within the case 12 and which may be coiled or lapped therethrough, if desired, so that the liquid in passing through portion 17 will be conveyed by an indirect or circuitous route therethrough. Portions 16 and 17 are connected by portions 18 and 19, portion 18 communicating with the outlet end of portion 16 and with the inlet end of portion 17 while portion 19 communicates with the outlet end of portion 17 and the inlet end of portion 16.

A pump 20 of any suitable construction is disposed in portion 19 of the conduit and is adapted to be driven by means of any suitable form of conventional motor 21 for pumping the liquid heretofore referred to and for circulating it endlessly from the pump 20 around the cooling coil 11 back through the casing 12, back through the pump 20 and thence again around the cooling coil 11.

On either side of the pump 20 is disposed a shut-off valve 22 by means of which the fluid heretofore referred to may be retained within the major portion of the conduit 13 should it be necessary to remove the pump 20 so that only that portion of the fluid disposed between the two valves 22 would be lost.

Cooling coil 11 after being in operation for a short time, particularly where it is necessary to keep the refrigerator 10 at a low temperature at

about or below the freezing point, will collect frost which will form a coating around the coil 11 and thereby tend to insulate it and prevent it from properly functioning for cooling the refrigerator 10. By operating the motor 21 to drive pump 20 the fluid with which the conduit 13 is filled will be circulated therethrough and in passing through portion 16 will melt the frost on the coil 11 and be cooled by contact therewith. This cooled liquid will then pass through portion 18 to portion 17 which will be at a temperature higher than the temperature of the liquid passing therethrough due to the fact that the showcase or container 12 is at normal temperature or at a temperature higher than the coil 11. The liquid while passing through portion 17 will therefore form a refrigerating coil or surface which will cool the case 12 and which will be in turn heated by the temperature therein so that when it again reaches the portion 16 it will be at a higher temperature to more effectively melt the frost on the cooling coil 11. It will thus be seen that when the pump 20 is in operation portion 16 will constitute a heating coil of tubular form through which a heated liquid is being constantly circulated and which has been heated by passing through casing 12 which is at a higher temperature, while the portion 17 will form a cooling coil or pipe line through which a fluid is being constantly circulated which has been previously precooled by being passed through and around the cooling means 11.

The apparatus employed not only functions as an attachment for cooling units to defrost the refrigerating surfaces thereof while said units are in operation and without effecting the normal operation thereof, but also forms an attachment whereby a conventional cooling unit may be employed to cool a zone or container separate from the container in which the cooling unit is mounted but which requires cooling to a temperature somewhat higher than the temperature of the container in which the cooling unit is disposed.

The apparatus as illustrated in Figure 2 corresponds with the apparatus illustrated in Figure 1 with certain slight modifications which will now be described and which include a by-pass designated generally 23 which is connected at one end to the portion 18 and at its opposite end to the portion 19 so that said by-pass is disposed between portions 16 and 17 and between the pump 20 and portion 17. In this modified form of the apparatus a shut-off valve 24 is disposed adjacent the inlet end of portion 17 while the by-pass 23 is provided with shut-off valves 25 adjacent its opposite ends. The intermediate portion of the by-pass 23, between the valves 25, is coiled spirally around a heating element 26 of any conventional construction which may be heated by any suitable means, not shown, for heating the coiled portion of by-pass 23 and the liquid passing therethrough.

By opening valve 22 and valve 24 and closing the valves 25, the apparatus as illustrated in Figure 2 will function in exactly the same manner as the apparatus illustrated in Figure 1 and heretofore described. If it is necessary to completely and quickly defrost the refrigerator 10, this may be more readily accomplished by shutting valve 24 and the valve 22 adjacent the portion 17, and opening both valves 25 after which element 26 is heated in its conventional manner and the pump 20 put in operation so that the liquid within that portion of the conduit 13 which includes portion 16, by-pass 23, and portions 18 and 19 between by-pass 23 and portion 16, will be circulated by the pump around the element 26 to be heated around the coil 11 and back around the element 26 so that coil 11 will be very quickly and effectively defrosted. If desired, motor 21 may be in the form of an electric motor which can be manually operated, by a switch, not shown, or which may be automatically operated by a thermostat and switch, not shown, mounted in casing 12 for cooling this casing when its temperature reaches a predetermined point.

The conduit 13 may be formed of a non-corrosive metal and corrosion and electrolysis will be further prevented by the fact that the liquid passing through the conduit does not come in contact with the coil 11. Furthermore, the liquid in conduit 13 is kept constantly sealed, except when said conduit is being refilled, to insure a clean liquid being circulated through the conduit 13 at all times, thereby eliminating the danger of dilution by moisture and air and of contamination by foreign matter such as frequently occurs in open tank systems. In providing the portion 17 of the conduit 13 a simple method is employed for adding new units to existing refrigerating systems without actually connecting with the conduits of said systems.

Various modifications and changes in the construction and arrangement of the apparatus are contemplated and may obviously be employed, and the right is therefore expressly reserved to make such variations and changes as do not depart from the spirit and scope of the invention as hereinafter defined by the appended claim.

I claim as my invention:

An endless conduit having a portion coiled around a cooling coil to be defrosted, a heating unit, a portion of said conduit being coiled around said heating unit, shut-off valves at opposite ends of said last mentioned portion, a by-pass around said last mentioned portion extending through an enclosed container, shut-off valves at opposite ends of said by-pass, said conduit being adapted to be filled with a liquid having a low freezing point, and a driven pump disposed in the conduit, between its first mentioned portion and its last mentioned portions, for circulating the liquid through the conduit.

PETER A. NELSON.
